UNITED STATES PATENT OFFICE.

THOMAS HOLT, OF TARRYTOWN, NEW YORK, ASSIGNOR TO THE HOLT-LYON COMPANY, OF TARRYTOWN, NEW YORK, A CORPORATION OF NEW YORK.

CARPET-BEATER.

No. 880,531.

Specification of Letters Patent.

Patented March 3, 1908.

Application filed May 3, 1904. Serial No. 206,192.

To all whom it may concern:

Be it known that I, THOMAS HOLT, a citizen of the United States of America, and a resident of Tarrytown, Westchester county, 5 New York, have invented certain new and useful Improvements in Carpet-Beaters, of which the following is a specification.

My invention relates to improvements in carpet beaters, and the object of my invention is to provide an improved instrument 10 constructed of wire, bent in such a manner as to present a flat extended head, the wires separated and rigidly supported, thereby making an inexpensive and effective carpet beater. I attain this object by means of the mechanism illustrated in the accompanying drawings, in which:

Figure 1 is a plan. Fig. 2 is a plan of one 20 of the bended wires A. Fig. 3 is a plan of the bended wire B. Fig. 4 is a plan of the tie wire C. Fig. 5 is a plan of a modified form of my invention. Fig. 6 is a plan of another modified form of my invention. Fig. 25 7 is a longitudinal section through the handle. Fig. 8 is detailed perspective view of the crossing of the wires in Fig. 7 showing the kink.

Similar letters refer to similar parts throughout the several views.

30 In order to construct a carpet beater which shall be strong and flexible, and at the same time enduring and effective, and which may be put upon the market at a reasonable cost, I have invented one made of wire, which may 35 be bent in several different ways to form the head, as shown in the various forms of the accompanying drawings, each of which shall present an extended portion preferably united at points of intersection, making a firm and 40 rigid head connected with a supple shank and handle.

I preferably bend a wire in the form shown at A Figs. 1 and 2, the two portions, a, of the wire, A, being arranged parallel to each other, 45 after being bent and separated to form the head portion thereof. I form a second wire, as shown by B in Fig. 3, bent in substantially the same manner and form as A, having parallel portions, b, forming the shank.

50 I preferably cause the portions, B, A, to extend in opposite directions from their respective shanks, a, b, as shown in Figs. 1, 2 and 3, forming the extreme beater ends. I then take the two wires, A and B, and place 55 them in connection with each other, in such

a manner that the wire A shall extend toward one side and the wire B toward the opposite side, and so that one portion, a' of the wire A shall extend over one portion b' of the wire B, and another portion a² of the wire A 60 shall extend under the portion b' of the wire B, and the portion a² of the wire A extend over the portion b² of the wire B. Thus the two wires, A and B, are at their heads interwoven with each other; at the places of intersection of the wires A and B, I may kink the wires, as at e, respectively, see Figs. 6 and 8, for the purpose of maintaining a permanent 65 place of contact. I then twist the shanks, a, b, of the wires, A and B, as shown at D, 70 preferably leaving a portion of the shank, E, below the twisted portion, D, near the head without being twisted, and near the end of the handle I preferably twist the wires as at F.

75 For the purpose of tying the wires, A and B, together I use a wire, C, as shown in Figs. 1 and 4. This wire, C, is bent at about midway between its end, one portion thereof, c', adjacent to the bent part passes over the portion b' of the wire B, and under the portion a² of the wire A and under portion a' of wire A. The other portion, c, of the wire, C, adjacent to the bent part thereof passes over the wire, a², under the wire b' and over the 80 wire b². The ends, c and c', are twisted around with the wires, a, b. As thus arranged the portions, A and B, are held firmly 85 in contact with each other, bound together by the tie, C, the whole instrument making a 90 durable flexible beater.

For the purpose of securing the handle, H, on the end of the wires I preferably construct one of the wires, b, longer than the adjacent wire, a, and the other wire, b, driving the 95 handle, H, upon the said projecting wire, said projecting wire forcing an opening through the handle. The other wires, a, b, extend into the handle a short distance, the projecting wire bent over at its end and turned 100 back into the end of the handle, forming a loop, J, to prevent the handle from coming off or turning around. This construction of the handle, in which the ends of the wires, A, engage with the bottom of the opening in 105 the handle, H, see Fig. 7, prevents the handle from slipping up on to the shank, E, of the beater, while the projecting wire, b, passing through the end of the handle, H, and bent parallel with itself, with its end driven 110

back into the end of the handle prevents the handle from turning and coming off of the wires. The wires being twisted together within the handle and a short distance 5 above the handle adds strength to the portion of the beater most liable to strain.

I have shown in Fig. 5 the portions A' and B' fastened together without the use of the tie piece, C, and the shanks of one portion of 10 the wires, A' and B', twisted at K, their place of intersection.

What I claim as my invention and desire to secure by Letters Patent is:

1. A carpet beater comprising a wire having a shank portion and a looped portion; said looped portion projecting to one side of the shank portion; a second wire in substantially the same form as the first mentioned wire; said wires being united together, their 15 shank portions adjacent to each other, the looped portions extending in opposite directions crossing each other; a tie piece placed in connection with the intersecting wires of said loops, respectively, united to the shanks 20 aforesaid by twisting; a handle secured to the ends of the shanks, substantially as described.

2. A carpet beater comprising a wire having a shank portion and a looped portion; 30 said looped portion projecting to one side of the shank portion; a second wire formed in substantially the same form as the first mentioned wire; the looped portions crossing each other and extending in opposite directions; the shanks being united by twisting 35 the wires slightly below the loops; a handle secured to the end of the shank.

3. In a carpet beater having a shank constructed of wire; said wires twisted near their ends and having one wire longer than the others; a handle provided with a central longitudinally extended socket from one end of the handle to nearly the opposite end thereof; said twisted wires forming the shank portion of the beater placed in said socket in 40 said handle; the shorter ones engaging the bottom thereof; said longer wire extending through the bottom of said socket and back, parallel to itself into said handle to hold it in place, substantially as described. 50

4. A carpet beater comprising a wire provided with a looped portion and a shank portion; said looped portion extending to one side of the shank portion; a second wire substantially in the same form as the first mentioned wire; said wires being united together, the looped portions extending in opposite directions and crossing each other; the shank portions adjacent to each other; a tie piece placed in connection with the intersecting wires of said looped portions, respectively, and twisted around said shanks; 55 said wires forming the shank, being twisted at their ends; a handle secured to the end of the said shank, on the twisted portion thereof, but which twisted portion extends slightly above the handle, when in position, substantially as described. 60

Signed at Tarrytown, N. Y. this 25th day of April 1904.

THOMAS HOLT.
